UNITED STATES PATENT OFFICE.

WAYNE S. SEARLES, OF PROVIDENCE, RHODE ISLAND, ASSIGNOR TO UNIVERSAL OPTICAL CORPORATION, OF PROVIDENCE, RHODE ISLAND, A CORPORATION OF RHODE ISLAND.

OPHTHALMIC MOUNTING.

Application filed June 13, 1922. Serial No. 567,995.

To all whom it may concern:

Be it known that I, WAYNE S. SEARLES, a citizen of the United States, residing at Providence, in the county of Providence and State of Rhode Island, have invented certain new and useful Improvements in Ophthalmic Mountings, of which the following is a specification.

This invention relates to improvements 10 in the construction of ophthalmic mountings, more particularly to those constructed with non-metallic frames, and the object of this invention is to provide, primarily, an improved construction of joint 15 members by which the temple members are secured to the frame, and an improved means for securing one of the members of the joint to the end portion of the frame in such a way as to reduce the cost, and 20 render more practical and permanent the construction of the mounting.

With these and other objects in view, the invention consists of certain novel features of construction, as will be more fully described, and particularly pointed out in the appended claims.

In the accompanying drawings:

Figure 1 is a perspective view showing a non-metallic spectacle frame in which my 30 improved temple joint is employed.

Figure 2 is a sectional edge view of the frame at the joint, showing the arrangement of the joint spurs also the stop in the joint.

Figure 3 is a side view of the joint partly 35 in section illustrating the stop lugs of one of the members of the joint as engaging recesses in the other member of the joint for the purpose of providing a stop in the joint for limiting its opening motion.

Figure 4 is a side elevation of the joint showing the arrangement of the spurs and the arrangement of the stop in the joint.

Figure 5 is a view of the rear of the 45 end piece of the frame showing the transverse groove across the face thereof whereby the extremity of the end piece may be bent back into the position illustrated in dotted lines in Figure 2, to permit piercing 50 and positioning of the joint spur into the end piece after which this portion may be bent back to normal.

Figure 6 is a modification showing the

spur of one of the joint members as passing diagonally through the end piece and 55 secured therein.

Figure 7 is a side elevation showing another form of hinge in which the stop lug is formed on the middle member to engage 60 the back portion of the forked member of the hinge to limit its opening motion.

It is found in practice where the end pieces are turned back out of their normal plane, that, in operation, they have a tendency to spring back or straighten and so throw out of alignment their point of connection with the temple and, therefore, it is found of advantage to form these end pieces straight or on a line substantially 65 parallel with the plane of the side edges 70 of the lens frames so that the whole may be cut from a sheet of stock to remain or operate in their normal plane. It is also found of advantage to set the spur of one 75 of the hinge members into its end piece so that its axis will be substantially parallel with the plane of the side edges of the lens frame, and also to provide a stop in the joint within the circumference of the body portion thereof to limit the opening 80 swing of the temple member; and the following is a detailed description of means by which these results may be accomplished:—

With reference to the drawings, 10 designates the usual spectacle frame which is formed wholly or in part of non-metallic material such for instance as celluloid, zylonite or other suitable material and on the opposite extremities of this frame are 90 formed end pieces 11 integral therewith.

It is found of advantage to form the end pieces straight, instead of curving them back beyond the plane of the side edges of the frame for several reasons: first, the end piece remains permanently in its normal plane as cut from sheet stock; second, the temple member in swinging inwardly will lay flat against the inner edges of the frame to take up the minimum space when folded; and third, the spur of the hinge may be more readily positioned in the end piece as presently described.

My special construction of joint is preferably formed of two members, one having 105 a prong or spur 13 to set into the temple

as shown in dotted lines in Figure 2, while the other has a prong spur 14 arranged to set into the end piece 11, which latter is preferably offset bodily inwardly from the inner face of the end piece 11 and its axis is preferably set so that when positioned therein it will be substantially in line with the plane of the inner face of the end piece, and to facilitate the connecting of this joint 10 member to the end piece and also to facilitate the setting of the spur thereinto, I preferably form a transverse groove 16 across the rear face of the end piece as best shown in Figure 5, into which groove is set the 15 body portion 17 of the hinge, whereby when heated the portion 18 of the end piece may be turned or bent back into the dotted position illustrated in Figure 2 thereby exposing the center of the end piece to be 20 drilled or bored to receive the spur of the joint after which the portion 18 is bent back into its normal shape where it will be flush with the outer edge of the temple.

In some instances instead of setting the 25 spur on a line parallel with the side edges of the lens frame, I may set the spur on an angle as illustrated in Figure 6, through the end piece and secure the same therein by means of a pin 19.

30 It is found in practice to be of advantage in the construction of hinges of this character to provide a stop in the hinge to limit the opening swing of the temple, and to do this in a simple and practical way I have 35 recessed at 21 the members 20 of the body portion of the joint 17, and I have provided the inner member 22 of the joint with a pair of transverse lugs 23 adapted to swing in the recesses 21 in the opposite member 40 and to bring up against the end walls 24 of these recesses thereby limiting the opening swing of the temple and in this construction the stop is formed entirely within the circle of the periphery of the body of the 45 joint thus forming a strong and durable stop without taking up extra room in the joint.

Another construction is to provide a hinge 50 with a stop lug 25 on the back portion of the body of the middle member, which is arranged to engage the back portion 26 of the forked member of the hinge at a point between its branches to limit the opening motion of the hinge.

55 My improved construction of end piece and joint member connected thereto, forms a practical construction which is strong and durable and efficient in its action.

The foregoing description is directed solely 60 towards the construction illustrated, but I desire it to be understood that I reserve the privilege of resorting to all the mechanical changes to which the device is susceptible, the invention being defined and limited 65 only by the terms of the appended claims.

I claim:

1. An ophthalmic mounting comprising a non-metallic frame having an end piece with its rear face disposed in a plane substantially parallel with that of the side edges 70 of the frame, a temple, a hinge for connecting the temple to said end piece, one member of said hinge having a spur set into said end piece in a line substantially parallel with the plane of said frame edges, and 75 means engaging the spur to lock it in the end piece.

2. An ophthalmic mounting comprising a non-metallic frame having an end piece with its rear face disposed in a plane substantially parallel with that of the side edges of the frame, a temple, a hinge for connecting the temple to said end piece, one member of said hinge having a spur set into said end piece, and the body portion of 80 said hinge member being provided with a stop for limiting the opening swing of the temple. 85

3. An ophthalmic mounting comprising a non-metallic frame having an end piece with its rear face disposed in a plane substantially parallel with that of the side edges of the frame, a temple, a hinge for connecting the temple to said end piece, one member of 90 said hinge having a spur set into said end piece, and a stop formed in said hinge within the circumference of its body portion for limiting the opening swing of the temple. 95

4. An ophthalmic mounting comprising a non-metallic frame having an end piece provided with a portion adapted to be temporarily displaced from normal position to facilitate positioning a joint spur in the 100 end-piece.

5. An ophthalmic mounting comprising a 105 non-metallic frame having an end piece provided with a portion adjustable from a plane substantially at right angles to the side edges of the frame to a plane substantially parallel thereto to facilitate positioning of 110 a spur in the end-piece.

6. An ophthalmic mounting comprising a non-metallic frame having an end piece, said end piece having a portion adjustable from a plane substantially at right angles to the 115 side edges of the frame to a plane substantially parallel thereto to facilitate positioning of a spur in the end piece.

7. An ophthalmic mounting comprising a non-metallic frame having an end piece with its rear face disposed in a plane substantially parallel with that of the side edges of the frame, the end piece having a portion adjustable from a plane substantially at right angles to the side edges of the frame 125 to facilitate positioning of a spur, the adjustable member forming an abutment or stop for the temple.

In testimony whereof I affix my signature.
WAYNE S. SEARLES.
